UNITED STATES PATENT OFFICE.

JONATHAN O. FOWLER, JR., OF NEW YORK, N. Y.

TYPE-WRITING MACHINE.

SPECIFICATION forming part of Letters Patent No. 655,652, dated August 7, 1900.

Original application filed November 8, 1892, Serial No. 451,412. Divided and this application filed June 10, 1896. Serial No. 594,931. (No model.)

To all whom it may concern:

Be it known that I, JONATHAN O. FOWLER, Jr., a citizen of the United States, and a resident of New York, in the county and State of New York, have invented a certain new and useful Type-Writing Machine, of which the following is a specification, the same being a division of my application filed November 8, 1892, Serial No. 451,412.

10 My invention relates to type-writers having a plurality of keys, and has for its object the provision of features of novelty whereby a type-writer comparatively simple in construction, inexpensive in manufacture, and 15 efficient in practical use may be organized.

To attain the desired end, my invention consists in the construction, arrangement, and operation of parts herein set forth.

In the drawings which form a part of this 20 specification, Figure 1 represents a side elevation, partly in section, of my type-writer; and Fig. 2 is a similar view, one of the keys being depressed. Fig. 3 is a plan view of the ends of my type-carriers, and Fig. 4 is a view 25 in detail of one of my keys.

Like letters of reference indicate like parts in all the views.

Referring particularly to the drawings, A and C denote two of my manual vertical keys 30 sustained in normal position in any suitable manner, as by springs D, each key being provided with working or movement-impacting means, as the enlarged lower portion $a\ c$, having an inclined lower edge. Intermediate a 35 suitable type-carrier constructed according to my invention, as the radially-disposed reciprocating type-carriers E, traveling in radially-disposed guides and working in the same and preferably-horizontal plane, and the 40 hereinbefore-described preferably-vertical keys, as A and C, is located suitable coacting mechanism, consisting in this instance of the following parts, which I term "engaging mechanism:" The type-carrier rod e is loosely 45 supported by suitable bearings within the frame or case of my type-writer and is furnished at its free end with the type-carrier proper, E, provided with type-faces $a^2\ c^2$ and with recesses $a^2\ c^2$, located under or rearward 50 of the same. The reciprocating or sliding horizontal bar F is also suitably supported,

preferably, in a horizontal position practically parallel with and below the type-carrier rod e, and is provided with circular studs or rolls f, constructed and arranged to engage 55 and work along the inclined lower edge of the keys with a traveling contact movement and is preferably held in normal forward position by means of the spring M, common to the two keys and serving to resist the forward stroke 60 of the type-carrier with an increasing tension, the shanks of the keys preventing the forward movement (beyond the normal position) of the same.

A flat pivoted rocking lever G, provided 65 with slots at both extremities, is fulcrumed at g and connected in a movable relation with the forward free extremity of the bar F by the stud or roll f^2 within its lower slot or groove, and is provided at its upper end with 70 an enlargement or disk, through which the stud or roll f^2 , forming the end of the spring L, carried by the type-carrier, passes. The pivoted rocking part G thus has a lower slot 75 to engage a stud or roll f^2 , actuated by one of the keys, and is also adapted to engage and actuate the type-carrier with a stud or roll and groove movement. Intermediate the type-carrier head or block E and the disk of the lever G, I preferably place a flexible connection, consisting in this instance of a spiral spring L, passing around the type-carrier rod e and located between the lever G and the type-carrier block E. 80

It will be observed that the working portions of the keys are constructed and arranged to descend and rise again in a vertical line and in one plane. Each key is thus provided with projecting and recessed portions constructed and arranged to move vertically—as, for instance, the enlarged lower portions a of the said key. Each such projecting and recessed mechanism is also constructed and arranged to become engaged upon the manipulation of the key, as follows: 85 Whenever a key is depressed, the enlarged portion a engages a stud or roll f of the bar F, thereby moving the same to the right or backward, the lever G being thereby rocked, which lever bears against the spring L, thus 90 causing the type-carrier E e to move forward or to the left. In order that the depression 100

of the different keys may cause a different letter to be printed when my key-action is used with the other mechanism herein shown, I provide a stop device controlled by the keys, whereby the movement of the type-carrier may be regulated, which stop device consists in the present instance of the pin e' of the type-carrier rod e and the arms $a' c'$, respectively connected with and controlled by the keys A and C. The vertical arms $a' c'$ serve as stops for the type-carrier, and in order to secure means for insuring the retention of the type-carrier in one of its limited differential forward positions as long as any key is depressed I provide means, as the closed tops $a^4 c^4$ of the arms $a' c'$, the said tops also serving to connect the said arms with the keys, which closed tops prevent some of the keys from being depressed sufficiently far for the arms $a' c'$ in descending to pass by or away from the stop, as the pin e' of the type-carrier rod e , and which tops therefore serve as retaining means in connection with the arms $a' c'$ to hold the pin e' adjacent to the said arms $a' c'$ and hinder the type-carrier head E from moving from its printing position as long as any key is depressed.

The type-carrier E e is not only prevented from advancing beyond the required printing-point by reason of the arms $a' c'$ being in the path of the forward movement of the stopping-pin e' , but is also prevented from receding by reason of the engagement of the impacting faces of the enlarged lower portions $a' c'$ of the keys A C with one of the studs or rolls f of the bar F, which holds the type-carrier E e forward, acting in connection with the rocking lever G. The arms $a' c'$, used in connection with the enlargements $a' c'$, thus prevent the type-carrier from moving in either a forward or rearward position from the printing-point.

Inasmuch as more than two keys may be used in my type-writer it is manifest that similar or equivalent means may be used for operating whatever number of type-carriers it may be deemed advisable to embody in a machine. For example, a series of radially-disposed type-carriers provided with three type-faces are shown in Fig. 3, each of which type-carriers may be actuated by three keys, constructed and arranged to operate the same in a manner similar to those described herein. I provide my machine with a common center gateway or printing-aperture J, preferably formed in a yielding plate, as of soft rubber, so that each individual type on each type-carrier when in alinement with the aperture can be thrust up to engage the paper on the platen. This aperture J is located in front of the type-carriers and in the same vertical plane with each type-carrier, the type-faces of the radially-disposed type-carriers being inclined as regards their longitudinal axes so as to come into proper alinement when at the printing-point. When a key, as C, is depressed by such depression or initial move-

ment, the enlargement c causes the type-carrier E e to advance by means of the intermediate stud or roll f , bar F, stud f^2 , lever G, and stud f^3 of the spring L. The continued depression of the key causes the arm c' to engage the pin e' of the type-carrier rod, whereupon the type-face c^2 will be positioned immediately below the printing-slot J.

Inasmuch as the type-carrier E e is prevented from moving forward by the stop e' it is manifest that the stud or roll f may either move along the vertical shank of the enlargement c , if the key is pushed down farther, or else that the depression of the key may cause the hammer K to be operated by the pin c^3 of the arm c' , the additional movement of the bar F and rock-lever G causing the compression of the spring L. By means of the engagement of the pointed head of the hammer K with the recess c^{12} of the type-carrier E the corresponding character c^3 may be imprinted upon the paper on the platen.

It is manifest that various omissions of some particulars could be made without materially affecting the essential features of my invention or the operation of the remaining parts, and I do not therefore wish to be limited to the specific structural details of the organization herein set forth. Obviously, the elements of the structure described may be located at an angle to the plane in which they are shown or they may be inverted, if desired. I accordingly use the words "vertical," "horizontal," and the like in a relative sense.

The relative positions of and the method of impacting the type faces and platen and also the location of the type-faces upon the type-carrier may be varied, and any desired style of platen and paper-carriage may be employed, and although only two keys are shown yet any one skilled in the art will be enabled to construct according to my invention a machine consisting of any required number of keys.

In this application I only claim the key-action, the other features shown and described being claimed in my application filed November 8, 1892, Serial No. 451,412, of which this is a division.

As it is evident that many changes in the construction and relative arrangement of parts might be resorted to without departing from the spirit and scope of my invention, I would have it understood that I do not restrict myself to the particular construction and arrangement of parts shown and described, but that such changes and equivalents may be substituted therefor, and that

What I claim as my invention is—

1. The combination, with a plurality of type-carriers E constructed and arranged to work back and forth, and with a common center gateway or aperture J, to register with each of the type-carriers, upon being brought to the printing-point, and located in front of the same, of a plurality of keys A, and of a plu-

5 tality of intermediate engaging means, consisting of rocking pivoted parts G, and sliding horizontal parts F, each constructed and arranged to engage a key with a traveling contact movement, the impacting portions a, f, of the key and said engaging means being relatively circular—as a stud or roll f²—and an incline a, along which the stud or roll works, and a spring M to resist the forward 10 stroke of the type-carriers with an increasing tension.

2. The combination, with a plurality of type-carriers constructed and arranged to work back and forth, and with a common center 15 gateway or aperture to register with each of the type-carriers, upon being brought to the printing-point, and located in front of the same, of a plurality of keys, and of a plurality of engaging means intermediate the type-carriers and keys, and each provided with means constructed and arranged to engage a key with a traveling contact movement, the impacting portions of the key and said engaging means being relatively circular,—as a stud or roll—and an incline along which the stud or 25 roll works.

3. The combination, with a plurality of type-carriers constructed and arranged to work back and forth, and with a common center 30 gateway or aperture to register with each of the type-carriers, upon being brought to the printing-point, and located in front of the same, of a plurality of keys, and of a plurality of engaging means, intermediate the type-carriers and keys, and each provided with a pivoted rocking part having a slotted lower portion to engage a stud or roll actuated by one of the keys, and also adapted to engage 35 and actuate one of the reciprocating type-carriers.

4. The combination, with a plurality of type-carriers constructed and arranged to work back and forth, and with a common center gateway or aperture to register with each of the type-carriers, upon being brought to the printing-point, and located in front of the same, of a plurality of keys, and of a plurality of engaging means, intermediate the type-carriers and keys, and each provided with a pivoted rocking part having a slotted lower portion to engage a stud or roll actuated by one of the keys, and also adapted to engage 45 and actuate one of the reciprocating type-carriers with a stud or roll and groove movement.

5. The combination, with a plurality of type-carriers constructed and arranged to work back and forth, and with a common center gateway or aperture to register with each of the type-carriers, upon being brought to the printing-point, and located in front of the same, of a plurality of keys, and of a plurality of engaging means intermediate the type-carriers and keys, and each provided with a pivoted rocking part having a slotted lower portion to engage a stud or roll actuated by 55 one of the keys, and also adapted to engage

and actuate one of the reciprocating type-carriers, and also provided with means constructed and arranged to engage a key with a traveling contact movement.

6. The combination, with a plurality of radially-disposed type-carriers constructed and arranged to work back and forth in a horizontal plane, and with a common center gateway 75 or aperture to register with each of the type-carriers, upon being brought to the printing-point, and located in front of the same, and in the same vertical plane with each type-carrier, of a plurality of keys, and of a plurality of engaging means, intermediate the type-carriers and keys, and each provided with means constructed and arranged to engage a key with a traveling contact movement, the impacting portions of the key and 80 said engaging means being relatively circular,—as a stud or roll—and an incline along which the stud or roll works.

7. The combination, with a plurality of radially-disposed type-carriers constructed and 85 arranged to work back and forth in a horizontal plane, and with a common center gateway or aperture to register with each of the type-carriers, upon being brought to the printing-point, and located in front of the same, and 90 in the same vertical plane with each type-carrier, of a plurality of keys, and of a plurality of engaging means, intermediate the type-carriers and keys, and each provided with a pivoted rocking part having a slotted 95 lower portion to engage a stud or roll actuated by one of the keys, and also adapted to engage 100 and actuate one of the reciprocating type-carriers.

8. The combination, with a plurality of radially-disposed type-carriers constructed and arranged to work back and forth in a horizontal plane, and with a common center gateway or aperture to register with each of the type-carriers, upon being brought to the printing-point, and located in front of the same, and in the same vertical plane with each type-carrier, of a plurality of keys, and of a plurality of engaging means, intermediate the type-carriers and keys, and each provided 110 with a pivoted rocking part having a slotted lower portion to engage a stud or roll actuated by one of the keys, and also adapted to engage 115 and actuate one of the reciprocating type-carriers with a stud or roll and groove movement.

9. The combination, with a plurality of radially-disposed type-carriers constructed and arranged to work back and forth in a horizontal plane, and with a common center gateway or aperture to register with each of the type-carriers, upon being brought to the printing-point, and located in front of the same, and in the same vertical plane with each type-carrier, of a plurality of keys, and of a plurality of engaging means, intermediate the type-carriers and keys, and each provided with a pivoted rocking part having a slotted lower portion to engage a stud or roll actuated by 125 130

one of the keys, and also adapted to engage and actuate one of the reciprocating type-carriers, and also provided with means constructed and arranged to engage a key with 5 a traveling contact movement.

10. A plurality of keys A, each provided with a spring D, to hold the same in normal position, and each constructed and arranged to actuate horizontally-reciprocating means carrying type-faces, in combination with said reciprocating means, radially-disposed guides for the same, a common spring M, to resist the forward stroke of the said means with an increasing tension, and pivoted rocking means 10 G, provided with slots at both extremities to coact respectively with a roll f^2 actuated by one of the keys, and with a stud or roll b^2 carried by the type-carrier.

11. A plurality of keys, each provided with a spring to hold the same in normal position, and each constructed and arranged to actuate horizontally-reciprocating means carrying type-faces, in combination with said reciprocating means, radially-disposed guides for the same, means for impelling said type-faces provided with a pivoted rocking part having a slotted lower portion to engage a stud or roll actuated by one of the keys, and a spring to resist the forward stroke of the said means 25 with an increasing tension.

12. A plurality of keys, each provided with a spring to hold the same in normal position, and each constructed and arranged to actuate horizontally-reciprocating means carrying type-faces, in combination with said reciprocating means, radially-disposed guides for the same, means for impelling said type-faces provided with a pivoted rocking part having a slotted lower portion to engage a stud or 30 roll actuated by one of the keys, and also provided with means constructed and arranged to engage a key with a traveling contact movement, and a spring to resist the forward stroke of the said means with an increasing tension.

13. A plurality of keys, each provided with a spring to hold the same in normal position, and each constructed and arranged to actuate horizontally-reciprocating means carrying type-faces, in combination with said reciprocating means, radially-disposed guides for the same, a common center gateway or aperture to register with each of the type-faces, upon being brought to the printing-point, means for impelling said type-faces provided with a pivoted rocking part having a slotted lower portion to engage a stud or roll actuated by one of the keys, and a common spring to resist the forward stroke of 55 the said means with an increasing tension.

14. A plurality of keys, each provided with a spring to hold the same in normal position, and each constructed and arranged to actuate horizontally-reciprocating means carrying type-faces, in combination with said reciprocating means, radially-disposed guides for the same, a common center gateway or

aperture to register with each of the type-faces, upon being brought to the printing-point, and a common spring to resist the forward stroke of the said means with an increasing tension, and pivoted rocking means provided with a slot at the lower part to engage a stud or roll actuated by one of the keys, and also adapted to engage one of the reciprocating type-carriers with a stud or roll and groove movement. 70

15. A plurality of keys, each provided with a spring to hold the same in normal position, and each constructed and arranged to actuate horizontally-reciprocating means carrying type-faces, in combination with said reciprocating means, radially-disposed guides for the same, a common spring to resist the forward stroke of the said means with an increasing tension, and pivoted rocking means provided with a slot at the lower part to engage a stud or roll actuated by one of the keys, and also adapted to engage one of the reciprocating type-carriers with a stud or roll 85 and groove movement. 90

16. A plurality of radially-disposed type-carriers, and a common center gateway or aperture to register with each of the type-faces, upon being brought to the printing-point, the type-face of each type-carrier being inclined so as to register in alinement with the said aperture, and means to impel the said type-carriers, provided with pivoted rocking means having a slot at the lower part 100 to engage a stud or roll actuated by one of the keys, and also adapted to engage one of the reciprocating type-carriers with a stud or roll and groove movement. 95

17. A plurality of radially-disposed type-carriers, located in a horizontal plane, and a common center gateway or aperture to register with each of the type-faces, upon being brought to the proper printing-point, the face of each type-carrier being inclined so as to 105 register in alinement with the said aperture, and means to reciprocate said type-carriers provided with pivoted rocking means having a slot at the lower part to engage a stud or roll actuated by one of the keys, and also 110 adapted to engage one of the reciprocating type-carriers with a stud or roll and groove movement. 115

18. The combination, with a plurality of type-carriers constructed and arranged to work back and forth, and with a common center gateway or aperture to register with each of the type-carriers, upon being brought to the printing-point, and located in front of the same, the type-face of each of the said type-carriers being inclined so as to register in alinement at the said aperture, of a plurality of keys, and of a plurality of engaging means, intermediate the keys and the type-carriers, and each provided with a pivoted rocking part having a slotted lower portion to engage a stud or roll actuated by one of the keys, and also adapted to engage and actuate one 120 of the said reciprocating type-carriers. 125

19. The combination, with a plurality of type-carriers constructed and arranged to work back and forth, and with a common center gateway or aperture to register with each of the type-carriers, upon being brought to the printing-point, and located in front of the same, the type-face of each of the said type-carriers being inclined so as to register in alinement at the said aperture, of a plurality of keys, and of a plurality of engaging means, intermediate the keys and the type-carriers, and each provided with a pivoted rocking part having a slotted lower portion to engage a stud or roll actuated by one of the keys, and also adapted to engage and actuate one of the reciprocating type-carriers, and also provided with means constructed and arranged to engage a key with a traveling contact movement.
20. The combination, with a plurality of radially-disposed type-carriers constructed and arranged to work back and forth in the same plane, and with a common center gateway or aperture to register with each of the type-carriers, upon being brought to the printing-point, and located in front of the same, and in the same vertical plane with each type-carrier, the type-face of each of the said type-carriers being inclined so as to register in alinement at the said aperture, of a plurality of keys, and of a plurality of engaging means, intermediate the keys and the type-carriers, and each provided with a pivoted rocking part constructed and arranged to be actuated at its lower extremity with a stud or roll and slot movement, and also adapted to actuate one of the reciprocating type-carriers.
21. The combination, with a plurality of radially-disposed type-carriers constructed and arranged to work back and forth in the same plane, and with a common center gateway or aperture to register with each of the type-carriers, upon being brought to the printing-point, and located in front of the same, and in the same vertical plane with each type-carrier, the type-face of each of the said type-carriers being inclined so as to register in alinement at the said aperture, of a plurality of keys and of a plurality of engaging means, intermediate the type-carriers and keys, and each provided with a pivoted rocking part constructed and arranged to be actuated at its lower extremity with a stud or roll and slot movement, and also adapted to engage a key with a traveling contact movement.
22. The combination, with a plurality of radially-disposed type-carriers constructed and arranged to work back and forth, and with a common center gateway or aperture to register with each of the type-carriers, upon being brought to the printing-point, and located in front of the same, and also of a plurality of radially-disposed guides for said type-carriers, and of a plurality of keys, and pivoted
- rocking means constructed and arranged to be actuated at its lower extremity with a stud or roll and slot movement, and also adapted to engage one of the reciprocating type-carriers with a stud or roll and groove movement.
23. The combination, with a plurality of radially-disposed type-carriers constructed and arranged to work back and forth, and with a common center gateway or aperture to register with each of the type-carriers, upon being brought to the printing-point, and located in front of the same, and also of a plurality of radial guides for the said type-carriers, and of a plurality of keys, and of a plurality of engaging means, intermediate the type-carriers and keys, and each provided with a pivoted rocking part constructed and arranged to be actuated at its lower extremity with a stud or roll and slot movement, and also adapted to actuate one of the reciprocating type-carriers.
24. The combination, with a plurality of radially-disposed type-carriers constructed and arranged to work back and forth in the same plane, and with a common center gateway or aperture to register with each of the type-carriers, upon being brought to the printing-point, and located in front of the same, and also of a plurality of radially-disposed guides for the said type-carriers, and of a plurality of keys, and of a plurality of engaging means intermediate the type-carriers and keys, and each being provided with a pivoted rocking part constructed and arranged to be actuated at its lower extremity with a stud or roll and slot movement, and also adapted to actuate one of the reciprocating type-carriers, and also provided with means constructed and arranged to engage a key with a traveling contact movement.
25. A plurality of keys, each provided with a spring to hold the same in normal position, and each constructed and arranged to actuate radially-disposed means reciprocating in the same plane and carrying type-faces, and a common spring to resist the forward stroke of the said means with an increasing tension, in combination with a common center gateway or aperture to register with each of the type-faces, upon being brought to the printing-point, the type-faces of each type-carrier being inclined so as to register in alinement with the said aperture, and pivoted rocking means constructed and arranged to be actuated at its lower extremity with a stud or roll and slot movement, and also adapted to engage one of the reciprocating type-carriers with a stud or roll and groove movement.
- In testimony of the foregoing specification I do hereby sign the same, in the city of New York, in the county and State of New York, this 9th day of January, A. D. 1896.
